ENGRAVING TOOL

Harry C. Brown, San Antonio, Tex.

Application August 27, 1954, Serial No. 32,060

Term of patent 14 years

(Cl. D54—13)

(Granted under Title 35, U. S. Code (1952), sec. 266)

*Fig. 1.**Fig. 2.**Fig. 4.**Fig. 5.**Fig. 6.**Fig. 7.*To all whom it may concern:

The invention described herein may be manufactured and used by or for the Government for governmental purposes without the payment of any royalty thereon.

Be it known that I, Harry C. Brown, a citizen of the United States of America, residing at 1315 West Wildwood Drive, San Antonio, Texas, have invented a new, original, and ornamental Design for an Engraving Tool, of which the following is a specification, reference being had to the accompanying drawing, forming part hereof.

Fig. 1 is a perspective view of an engraving tool showing my new design;

Fig. 2 is a plan view thereof;

Fig. 3 is a side elevational view;

Fig. 4 is a front elevational view looking in the direction of arrow "a" of Fig. 3;

Fig. 5 is a fragmentary rear elevational view, looking in the direction of arrow "b" of Fig. 3;

Fig. 6 is a vertical sectional view taken on the line 6-6 of Fig. 2, looking in the direction of the arrows; and Fig. 7 is a vertical sectional view taken on the line 7-7 of Fig. 2, looking in the direction of the arrows.

I claim:

The ornamental design for an engraving tool, as shown.
